Primary Examiner — Sandra S Snapp*Assistant Examiner* — Ieisha N Price(74) *Attorney, Agent, or Firm* — Cramer Patent & Design, PLLC; Aaron R. Cramer(57) **CLAIM**

The ornamental design for a weed trimmer attachment, as shown and described.

DESCRIPTION

FIG. 1 is a perspective top front left view of a weed trimmer attachment, showing my new design;

FIG. 2 is a bottom rear right view thereof;

FIG. 3 is a front elevation view thereof, with a rear elevation view being identical;

FIG. 4 is a right elevation view thereof, with a left elevation view being identical;

FIG. 5 is a top plan view thereof;

FIG. 6 is a bottom plan view thereof; and,

FIG. 7 is an enlarged exploded view of FIG. 2 taken from indication circle 7.

The broken lines represent the boundary area of an unclaimed attachment aperture and form no part of the claimed design.

1 Claim, 6 Drawing Sheets(56)
